MOLD FOR GROUND MEAT

John S. Peterson, 7761 E. 11th St., Westminster, Calif.

Filed Mar. 28, 1960, Ser. No. 59,904

Term of patent 14 years

(Cl. D44—1)

FIGURE 1 is a perspective view of a mold for ground meat, showing my new design;

FIGURE 2 is a side elevation thereof;

FIGURE 3 is a perspective view of the mold as seen from a relatively low elevation; and

FIGURE 4 is an end elevation.

I claim:

The ornamental design for a mold for ground meat, substantially as shown.
